UNITED STATES PATENT OFFICE.

CLARA E. WATSON, OF EXETER, NEW HAMPSHIRE.

DESIGN FOR A STOVE-BRUSH.

SPECIFICATION forming part of Design No. 28,096, dated December 28, 1897.

Application filed August 3, 1897. Serial No. 646,981. Term of patent 14 years.

To all whom it may concern:

Be it known that I, CLARA E. WATSON, a citizen of the United States, residing at Exeter, in the county of Rockingham and State 5 of New Hampshire, have invented and produced a new and original Design for a Stove-Brush, of which the following is a specification, reference being had to the accompanying drawings, forming a part thereof.

10 In the drawings, Figure 1 represents a perspective view of a stove-brush showing my new design. Fig. 2 is a vertical central longitudinal section of the same.

As shown in the drawings, the leading or 15 material feature of my design is the triangular base 1, made up of three ribs or bars 2 2, slightly inclined, the bottom portion of said base being slightly concaved, forming sharp acute-angular edges between the bottom and 20 the ribs or bars 2 2. An upwardly-curved bail

or handle 4 connects the rear rib 2 with the angularly-arranged side ribs at their meeting-point. That part of the device included between the angularly-arranged ribs 2 2 is hollow, and the bottom portion of the base is 25 formed by a thin strip, sheet, or web of material, the under side of which, as heretofore stated, is slightly concaved.

Having now described my invention, what I claim as new, and desire to secure by Letters Patent, is—

The design for a stove-brush as herein shown and described.

In testimony whereof I affix my signature in the presence of two witnesses.

CLARA E. WATSON.
